**COMBINED SEAT AND LIQUID TANK FOR
AN INDUSTRIAL POWER-DRIVEN FLOOR
SCRUBBER**

Walter G. Ashton, Stone Park, Ill., assignor to Star
Industries, Inc., Chicago, Ill., a corporation of
Illinois

Filed June 19, 1968, Ser. No. 12,434

Term of patent 14 years

Int. Cl. D15—06
U.S. Cl. D49—9.1

Fig. 2.

Fig. 3.

FIG. 1 is a perspective view showing my new design for a combined seat and liquid tank for an industrial power-driven floor scrubber, the latter being shown in dotted lines and constituting no part of the invention;

FIG. 2 is a side elevational view thereof, the opposite side being substantially the same and the top being substantially plain;

FIG. 3 is a rear view thereof.

I claim:

The ornamental design for a combined seat and liquid tank for an industrial power-driven floor scrubber, as shown and described.
